UNITED STATES PATENT OFFICE.

WILLIE M. AGEE, OF ELMER, MISSOURI.

COMBINED LOAD-BINDER AND BRAKE ATTACHMENT.

1,099,153.

Specification of Letters Patent.

Patented June 9, 1914.

Application filed November 18, 1912. Serial No. 732,159.

To all whom it may concern:

Be it known that I, WILLIE M. AGEE, a citizen of the United States, residing at Elmer, in the county of Macon and State of Missouri, have invented certain new and useful Improvements in Combined Load-Binders and Brake Attachments, of which the following is a specification.

My invention relates to new and useful improvements in hay racks, and more particularly to hay ladders for racks and the object of my invention is to provide an improved hay ladder carrying a rotatable drum upon which the binding rope for binding the hay upon the rack may be wound to tighten the same when in use.

A further object of my invention is to provide the ladder with a second drum upon which a rope, cable, wire or other suitable connection for operating the brake of the rack may be wound.

A further object of my invention is to provide a novel means for mounting the ladder in position upon the rack so that it may be lowered when the rack is empty and raised to vertical position when the rack is to be loaded, the brake applying drum being operable in either position of the ladder. And a still further object of my invention is to provide a roller upon which the base of the ladder is swingingly mounted, the roller being so arranged as to provide not only a bearing for the ladder, but also a guide for the brake operating member and a support for the binding rope.

With these and other objects in view, my invention will be more fully described, illustrated in the accompanying drawings, and then specifically pointed out in the claims which are attached to and form a part of this application.

In the drawings: Figure 1 is a side elevation of my improved rack when loaded, the position of the binding rope being shown in dotted lines; Fig. 2 is a detail sectional view of the ladder employed in connection with the rack, portions of the rack body and supporting roller being broken away; Fig. 3 is a vertical section on the line 3-3 of Fig. 2; Fig. 4 is a perspective view of the ladder supporting roller and ladder detached from the rack.

Corresponding and like parts are referred to in the following description and indicated by the same reference characters throughout the drawings.

My improved hay ladder and its binding rope and brake operating attachments may be applied to any form of hay rack and for the sake of clearness are illustrated in connection with a rack 10 including a body having longitudinally extending spaced side members 11 connected by a plurality of transverse frame members 12 carrying platform forming rails 13, this rack body being supported upon any preferred form of running gear 14 having any suitable brake mechanism such as that conventionally shown at 15 and including an operating lever 16 pivoted at 17 to the wagon.

My invention includes primarily a hay ladder 18 which is swingingly mounted upon a supporting roller 19 and which carries devices for tightening the binding rope and for operating the brake mechanism. The supporting roller 19 consists of a length of relatively large metallic piping 20 in the ends of which are positioned lengths of smaller piping 21, the free ends of which extend beyond the ends of the pipe 20 and are journaled in alined bores 22 formed in the longitudinal frame members 11. These smaller pipes 21 are held in position in the larger pipes by means of rivets or other suitable fastening devices 23 and the roller as a whole is held against longitudinal movement and the frame members 11 are protected from undue wear by means of washers 24 which surround the free ends of the pipes 21 bearing between the ends of the pipe 20 and the frame members 11.

The ladder proper 18 consists of vertically extending spaced side members 25 connected at their upper ends by a transverse brace member 26. The lower ends of the side members 25 are cut-away as best shown at 27, in Fig. 3 of the drawings, to form bearings for the roller 19 upon which the ladder is secured by U-shaped stirrups 28 and nuts 29, suitable wear plates 30 being interposed between the side members 25 and the nuts. It will be readily apparent that the roller may be mounted upon the rack with the ladder in advance of the same as shown in Fig. 3 of the drawings or with the ladder at the rear of the roller, the specific manner of mounting depending upon the general construction of the rack body, it of course being necessary to have a cross member of the rack body directly in advance of the ladder to support the same when raised and
